(57) **CLAIM**

The ornamental design for a tire, as shown and described.

DESCRIPTION

FIG. 1 is a perspective view of a full tire of the present application taken from a front and first side thereof; FIG. 2 is a front view thereof;

FIG. 3 is a side view thereof taken from the first side thereof; FIG. 4 is an enlarged, partial perspective view taken from the front and first side thereof taken along line 4-4 of FIG. 1;

FIG. 5 is an enlarged, partial front view thereof taken along line 5-5 of FIG. 2; and,

FIG. 6 is an enlarged, partial side view of the first side thereof taken along line 6-6 of FIG. 3.

The broken lines identifying the inner bead and the sidewall, and the sidewall therebetween, depict subject matter that forms no part of the claimed tire, and are included for the purpose of illustrating the full tire. Likewise, the tire interior forms no part of the claim. The tread pattern is understood to repeat throughout the circumference of the tire so that top, bottom, and rear views are the same as the front view. The other (second) side views are identical to the illustrated views of the first side.

The dashed broken lines indicating an enlargement portion of the design form no part of the claimed design.
